TLTING LEVEL

Bernard G. Howley, Dorchester, and Adolph W.
Holmberg, Quincy, Mass.

Application June 28, 1956, Serial No. 42,073

Term of patent 14 years

(Cl. D52—1)

Fig. 1

Fig. 2

Fig. 3

Figure 1 is a perspective view of a tilting level showing our new design.

Figure 2 is a side elevational view of the tilting level shown in Figure 1.

Figure 3 is an end elevational view as seen from the right side of Figure 2.

We claim:

The ornamental design for a tilting level, as shown.
